FEATHER WASHING MACHINE

Theodore M. Knox, Chicago, Ill.

Application August 3, 1939, Serial No. 288,249

3 Claims. (Cl. 141—1)

This invention relates to a feather washing machine, and it consists in the constructions, arrangements and combinations herein described and claimed.

5 It is the principal object of the invention to provide a washing machine in which the feathers undergoing treatment are thoroughly agitated in a cleansing fluid, the machine having means for collecting sediment or dirt washed from the 10 feathers, as well as means for withdrawing and collecting the washed feathers.

It is also an object of the invention to provide a novel collecting receptacle for washer feathers in which the receptacle may be removed to deposit 15 the feathers in a dryer.

Additional objects, advantages and features of invention will be apparent from the following description considered in conjunction with the accompanying drawing, wherein

20 Figure 1 is a side elevation of a washer, partly in section, constructed in accordance with my invention.

Figure 2 is a cross section on the line 2—2 of Figure 1.

25 Referring to Figure 1, there is illustrated a cylindrical drum 10 which may be of any desired proportions, which obviously will vary, depending on the capacity of the washer. The drum 10 is supported upon legs 11 from a floor 12.

30 The end walls of the drum 10 include bearings 13 in which there is revolvably mounted a shaft 14, upon which a plurality of paddles 15 are mounted, the paddles being spaced longitudinally along the shaft as clearly shown in Figure 1. 35 One end of the shaft 14 has keyed thereto a pulley or sprocket 16, by means of which the shaft 14 and associated paddles may be rotated.

Intermediate the length of the drum 10, at the upper side thereof, a hopper 17 is provided, permitting introduction of feathers to be washed.

40 Extended longitudinally of the drum 10 upon the lower side thereof, a channel 18 is formed, lying below the periphery of the drum, as clearly shown in Figure 2. A screen 19 of suitable mesh 45 is securely fixed across the channel 18 and extends from one end wall of the drum to the other end.

A water supply line 20 is shown, from which a pipe line 21 is extended upwardly adjacent one 50 end of the drum. The line 21 has a fitting 22 opening upon the channel 18, the latter having a valve 23 for controlling the flow of water into the channel, as will be explained hereinafter. The pipe 21 is continued upwardly to a point above 55 the drum where it is connected to a fitting 24

opening into the drum, and this fitting will also include a valve 25 for controlling the flow of water into the drum.

An outlet fitting 26 is embodied in the drum, the latter being substantially in the form of a T, 5 having a branch 27 connected to the drum at a point slightly above the channel 18 and a branch 28 at right angles thereto, the latter having a downwardly opening port 29, controlled by a reciprocating valve 30. The fitting 26 is of substantial size in order to permit ready flow of feathers therethrough for discharge into a bin 31.

As shown in Figure 1, a sewer line 32 is provided beneath the floor 12, and includes a pair of upright connections 33 and 34. The connection 33 opens directly into the bin 31, and the connection 34 terminates in a valve housing 35 for mounting of a plunger valve 36, the latter being manually actuated through an elongated stem 37 extended upwardly adjacent the bin 31. 20

A conduit 38 connected to the channel 18 adjacent the end thereof and opposite that of the water inlet 22 is provided, opening into the valve housing 35 above the valve 36.

Within the bin 31 a wire mesh basket 39 is 25 positioned of a size to fit freely therein and preferably includes short legs 40 for supporting the bottom of the basket above the floor of the bin to permit ready drainage of water from the basket.

30 In use, the feathers or down to be washed is deposited into the drum through the hopper 17, when the shaft 14 and associated paddles are rotated through rotation of the pulley or sprocket 16 from a suitable source of power, not shown. 35 The drum will first have been filled with water through actuation of the valve 25, and any cleansing compounds desired will also have been mixed with the water in the tank prior to deposit of the feathers. The feathers are agitated for any 40 desired length of time, this depending upon the condition of the feathers, and when thoroughly cleansed, the valve 36 is raised to a point above the branch pipe 27, thereby allowing water and feathers to flow, into the basket 39 within the 45 bin. During agitation of the feathers the dirt removed will settle into the channel 18, and by actuating valve 36 to open position, the dirt accumulated therein may be drawn off into the sewer line 32. The channel 18 may be flushed 50 by opening the valve 23 to admit water thereinto.

Obviously, where a rinsing of the feathers is found desirable, as will be the case in most instances, the valve 36 is opened to permit discharge of the water into the sewer line 32 and fresh

water admitted by way of the valve 25, during which the feathers are being agitated. A final rinse may be effected by closing the valve 36 and allowing clear water to enter the drum.

5. While I have specifically described the invention, this is by way of illustration only and I consider as my own all such modifications in structure as fairly fall within the scope of the appended claims.

10. I claim:

1. In a feather washing machine, a cylindrical drum having a feed hopper, an agitator revolubly mounted in the drum, said drum having a channel extending throughout the length of the drum below the lower periphery thereof, a foraminate partition between the drum and the channel, a T fitting having one branch connected to the drum above the channel, the other branch having a downwardly open port, a valve reciprocable in 15 said other branch to open and close the port, a bin beneath said other branch of the T fitting, a mesh basket removably seated in the bin to receive feathers and water discharged from the T fitting, a valved water inlet for the drum, a

valved water inlet for the channel at one end thereof, an outlet for the channel, a sewer line, the outlet of the channel being connected to the sewer line, valve means for controlling flow of liquid from the channel to the sewer line, and a waste pipe connected between the bin and the sewer line.

2. The structure of claim 1, in which the water outlet for the channel is at the end opposite the inlet.

3. In a feather washing machine, a cylindrical drum having a feed hopper, an agitator revolubly mounted in the drum, said drum having a channel in its lower portion extending throughout the length of the drum, a valved outlet for the drum 15 above the channel, a valved water inlet means for the drum, a valved outlet means for the channel at one end thereof, water inlet means opening upon the channel at the end opposite the outlet means, the valved outlet of the drum opening 20 upon a bin, and said bin having a constantly open water discharge.

THEODORE M. KNOX.
